JOHN H. KEYSER, OF NEW YORK, N. Y.

Letters Patent No. 62,962; dated March 19, 1867.

RADIATING ATTACHMENT FOR HOT-AIR FURNACES.

The Schedule referred to in these Letters Patent and making part of the same.

TO ALL WHOM IT MAY CONCERN:

Be it known that I, JOHN H. KEYSER, of the city and county of New York, in the State of New York, have invented a new and improved Radiator for Hot-Air Furnaces; and I do hereby declare that the following is a full, clear, and exact description thereof, reference being had to the accompanying drawings, making a part of this specification, in which—

Figure 1 is a front elevation of a portion of a hot-air furnace, having my improved radiator applied to it.

Figure 2 is a vertical section taken centrally through the furnace and regulator.

Figure 3 is a section through the radiator taken in the horizontal plane indicated by red line $z z$.

Similar letters of reference indicate corresponding parts in the several figures.

This invention relates to an improvement in the construction of radiators for hot-air furnaces; and consists in so constructing and arranging the flues through which the products of combustion pass, that two or more chambers or radiators arranged directly over the fire-chamber will be uniformly heated, and the products of combustion conducted upward to the highest chamber or radiator, and then caused to descend and pass out through the lowermost radiator, without the use of valves, dampers, or anything of the kind, as will be herein-after described.

To enable others skilled in the art to understand my invention, I will describe its construction and operation.

In the accompanying drawings I have represented my invention applied to a very simple form of furnace, consisting of a hollow base, A, an ash-pit, B, a fire-pot, C, and a dome or fire-chamber, D. Through the crown of the fire-chamber D an opening, a , is made for the upward passage of the heated products of combustion into the radiators, which are applied on top of said dome. The radiators consist of two hollow, double-convex, circular drums E F, arranged in horizontal planes, one above the other, and connected together at suitable distance apart by means of vertical pipes $b b b b$ and c , as shown in the drawings. The central pipe c forms a direct flue for the passage of the products of combustion from the fire-chamber D into the upper radiating drum F. This pipe passes unobstructedly through the lower drum E, and through the space between the two drums, and conducts the heated products of combustion into the centre of the upper drum, as indicated by the direction of the arrows in fig. 2. By thus delivering the products of combustion into the centre of the hollow drum F they will expand laterally in every direction and uniformly heat this drum. The vertical pipes b , which surround the central pipe c form descending flues for conducting the products of combustion from the upper drum F into the lower drum E, from which latter the products will be conducted off through the exit pipe g . The descending flues b are arranged around the central ascending flue c , for the purpose of diffusing the heated products of combustion throughout the two drums, and preventing such products from being carried off in one direct course, as would be the case if a single descending flue only were employed. The central ascending flue passing upward through the centre of the lower radiating drum, in combination with the descending flues leading from the drum F into drum E, and the escape flue g , leading from the drum E, enables one to effect the object above set forth without the use of a damper. The furnace and air-heating drums and radiating pipes are all enclosed by a jacket or casing which is not shown in the drawings, so that air admitted through the extended base A of the furnace will rise and circulate through the casing and pass off at or near the top thereof, in the usual manner. I am aware that it is not new to employ ascending and descending flues regulated by a damper as set forth in the Patent No. 59,173. In this arrangement the products of combustion take a direct course outward from the lower chamber when the damper is turned in one direction, and when it is turned in an opposite direction the products will ascend through one flue and pass downward and out through another flue, taking a direct course. This I do not desire to claim, for while it may serve the purpose claimed for it, it is not desirable for a hot-air furnace. By my plan a greater amount of heat is utilized and a greater area of radiating surface heated, while at the same time a damper is dispensed with. I do not confine my invention to the form and number of radiating drums described, nor to a definite number of vertical flues. I prefer to adopt the double-convex drums, as the dust and coal ashes which are carried into them will fall by their own gravity toward and through the vertical flues and thus return to the fire-pot. By my invention a greater number of radiating drums than two may be employed, provided the central flue be arranged upon the principle herein explained, and all the drums be connected together by descending flues. I do not desire to be understood as not employing any for regulating the draught of the furnace, as the usual dampers or regulators may be applied to the feed opening and ash-pit door. I do not wish to be under-

stood as laying claim of invention to anything shown or described in the patents of Adolphus Lotze, October 30, 1849, and M. B. Dyott, May 22, 1855; nor to anything shown and described in the withdrawn, rejected application of James Root, 1852.

Having described my invention, what I claim as new, and desire to secure by Letters Patent, is—

In the construction of radiators to be applied to hot-air furnaces, I claim the arrangement of a central ascending flue, *c*, passing through one or more radiating drums and leading into the centre of an upper drum, in combination with descending flues arranged around said flue, *c*, and communicating with the lowermost drum and an exit pipe *g*, so that without the use of a damper the products of combustion rising from the fire-chamber of the furnace shall be equally diffused throughout the said drums and pipes, substantially as described.

JOHN H. KEYSER.
